UNITED STATES PATENT OFFICE.

WILLIAM HUGHES, OF MAPLEWOOD, AND OTTO R. BIELER, OF MONTVALE, NEW JERSEY; SAID BIELER ASSIGNOR TO SAID HUGHES.

BOX-MAKING MACHINE.

1,335,686.

Specification of Letters Patent. Patented Mar. 30, 1920.

Application filed September 19, 1918. Serial No. 254,774.

To all whom it may concern:

Be it known that we, WILLIAM HUGHES, a citizen of the United States, and a resident of Maplewood, in the county of Essex and 5 State of New Jersey, and Otto R. BIELER, a subject of the Emperor of Germany, and a resident of Montvale, in the county of Bergen and State of New Jersey, have invented a new and Improved Box-Making 10 Machine, of which the following is a full, clear, and exact description.

Among the principal objects which the present invention has in view are,—to increase the number of boxes which may be 15 produced in a given time; to reduce the cost of production of said boxes; to reduce the quantity of material used in the manufacture of the boxes of the character herein disclosed; and to provide a smooth running 20 machine for performing the mechanical operations necessary to produce the boxes.

Drawings.

Figure 1 is a side view of the herein disclosed box-making machine;

Figs. 1^a, 1^b, 1^c, 1^d are detail views showing the cam members adapted to function in time relation;

Fig. 2 is a top plan view of the machine; 30 Fig. 3 is a vertical section on an enlarged scale, the section being taken as on line 3—3, Fig. 1, showing the parts of the machine in their inoperative or initial position;

Fig. 4 is a detail view on an enlarged scale, on line 4—4, Fig. 3, in vertical section showing the presser foot and edge wipers operatively engaged on the blank from which the box is constructed;

Fig. 5 is a detail view on an enlarged scale showing the suspension bracket and mounted for the folded-box delivery rollers;

Fig. 6 is a side view of the structure shown in Fig. 5, one of the rollers being 45 shown partially in section;

Figs. 7 to 13 inclusive are schematic views showing the successive steps in the manufacture of the box, the same being the product of the operation of the herein disclosed 50 machine.

Description.

It will be understood that boxes for the

manufacture of which the present machine is designed are what is known in the trade 55 as "tray boxes", or boxes wherein top-opening trays are placed in rectangular tubular cases or covers. The general idea of the cover is that shown in Fig. 13 of the drawings, the case or cover being open at both 60 ends.

When operating the present machine, it will be understood that blanks such as shown in Fig. 7 of the drawings are furnished. The blanks so furnished comprise scored card- 65 board pieces A, scored lines B and C having been impressed thereon to provide bending lines therefor. Adhesively attached to each of the members A is a paper facing D. The face D is so arranged that edge margins E 70 and F extend beyond the edges of the member A. These edge margins are furnished with a suitable adhesive before being placed in the machine upon the platen 20 to be operated upon by the machine. 75

The platen 20 is normally held by a supporting arm 21 flush with the operating table 22. The arm 21 is pivoted on a shaft 23 and is supported by a cam 24 on the driven shaft 25. A wheel 26 tracks on the perimeter of 80 the cam 24 and rocks the arm 21 to compress the spring 27, as shown in Fig. 1 of the drawings, when the platen 20 is elevated as shown in said figure.

The platen 20 is mounted at the end of 85 a plunger 28 with the lifting pin 29 of which the arms of a yoke 30 on the arm 21 engage. The movement of the plunger 28 upward and downward is controlled by a pin 31 which extends through a slot 32 90 formed in the said plunger. The pin 31 is mounted in a pendent frame 33 which is supported from the end of a table 34 and provides the bracket 35 in which the shaft 23 is mounted. 95

When the cam 24 permits, the spring 27 expands to depress the plunger 28 and the platen 20 at the upper end thereof. This movement of the arm 21 and platen 20 is perfectly timed with the operation of a 100 plunger 36 and a sleeve 37, both of which are reciprocated by the functioning of the cams 38 and 39, the said cams being best shown in Figs. 1^a and 1^c respectively.

The plunger 36 and sleeve 37 are tele- 105 scopically arranged, the former being dis-

posed within the latter, said sleeve having a bearing in the head of a bracket arm 40. From the back of the arm 40 is elevated a frame 41 in which are pins 42 and 43 which 5 form pivots for the rocking arms 44 and 45 provided for operating the plunger 36 and sleeve 37. The arms 44 and 45 have bifurcated yoke ends 46 and 47 respectively the jaws of which engage pins 48 and 49 set out 10 from the upper ends of the plunger 36 and the sleeve 37. The said plunger and sleeve are both held in line and limited as to movement by a pin 50 extending through the head of the bracket arm 40 and through 15 slots 51 and 52 in the said plunger and sleeve.

By comparison of the cams 38 and 39 it will be noted that the keyways 53 therein are shown in the drawings as in alinement. 20 The riser 54 of the cam 38 precedes in point of time the riser 55 of the cam 39. The connecting rods 56 and 57 and the rollers 58 and 59 are alined, as shown in Fig. 1 of the drawings; therefore, the roller 58 is lifted 25 by the riser 54 to the cam level 60 before the roller 59 is lifted by the riser 55. This operation of the cam 38 depresses the plunger 36 and the foot 61 carried thereby upon the platen 20 and the blank A resting thereon. 30 This position of the foot 61 and plunger 36 is to be seen in Fig. 4 of the drawings. The cam 39 quickly operates the connecting rod 57 to rock the arm 45 to depress the sleeve 37 and the bracket block 62 carried thereby 35 until the same rests directly above the foot 61. When the plunger 36 was moved to press the foot 61 upon the platen 20, the said platen slightly depressed, sufficient to permit the edges 63 of the opening in the table 40 22 to lift the edges E at the sides of the member A. When the sleeve 37 is depressed the cam level 64 holds the parts in position while the brush arms 65 are rocked on pivots 45 66 to advance wipers 67 over the edges of the member A, folding down the edges E upon the said member A as the wipers are passed thereover.

The arms 65 are rocked by the operation of the cam 68 on a cam wheel 69, shown best 50 in Fig. 1^a. It will be observed that the cam 68 is a short and sharp cam which rocks the arm 70 by means of the roller 71 thereon quickly to move the link 72 forward so that the arm 65 is swung toward the foot 61. 55 The arms 64 and 65 are operatively connected by a link 73, said link being pivotally connected to said arms at opposite sides of their respective pivots 66, thereby imparting to the lower end of the arms 64 and 65 relative opposite movements, thus both wipers 67 are moved inwardly simultaneously.

In time with the termination of the inward movement of the wiper 67 the cam lever 74 of the cam 38 further rocks the 65 arm 44 to depress the plunger 36 and the

foot 61. This movement of the foot 61 is coincident with the accommodating movement of the arm 21 and platen 20, the cam riser 75 of the cam 24 simultaneously alining with the wheel 26 of the arm 21 as the 70 roller 58 is affected by the cam lever 74. The recession of the arm 21 is produced by the expansion spring 27 and continues until the wheel 26 and roller 58 rest on the cam dwells 76 and 77 respectively. In this 75 position the platen 20 and foot 61 are depressed to the position indicated by broken lines in Fig. 4 of the drawings.

As seen in Fig. 4 of the drawings, the platen 20 approximates in width the width 80 of the casing member A. As seen in Fig. 3 of the drawings, the length of the platen 20 equals the distance from the scored line C to the second scored line B, beginning from the scored line C, on the said member A. The 85 length of the foot 61 is the same as the length of the platen 20. When the platen 20 and foot 61 are depressed through the opening in the table 22 the edges of said opening bend the member A upwardly on 90 the said score lines C and B above pointed out, the edges E of the paper facing D having been folded over the adjacent edges of the member A. The position of the blank at this stage of the proceedings is shown 95 in Fig. 10 of the drawings.

As seen best in Fig. 4 the platen 20 is brought to rest opposite the opening between the rollers 78 and 79. The opening between the rollers 78 and 79, as before seen 100 in Fig. 3 of the drawings, is in line with a plunger plate 80. The plate 80 is moved toward the platen 20 and is cut away to form a rabbet shoulder 81 which extends over to lay the short outstanding-portion G formed 105 from the member A when bent on the scored line C. This operation is performed during the period when the cam dwell 77 holds the foot 61 on the platen 20, which period indicates immediately that the plate 80 has 110 moved over the platen and the shoulder 81 has engaged the member A. The cam riser 82 of the cam 38 permits the rapid ascent of the plunger 36 and foot 61 to remove the said foot from the path of the advancing 115 plate 80.

The plate 80 is pivotally connected by a pin 83 with a lever 84. The lever 84 is fulcrumed on a stud shaft 85 extending from the underside of the table 34. The short 120 arm of the lever 84 has a roller 86 which tracks on the side of the cam wheel 69 in the path of a face cam 87. When the cam 87 rides under the roller 86, the free end of the lever 84 is moved toward the rollers 78 and 79 carrying the plate 80 in that direction. That portion of the member A extending 125 between the scored line B and the end of the member A having the edge F is elevated. When the plate 80 forces the member A be- 130

tween the rollers 78 and 79, the up-standing portion is at once folded down and pressed as the folded member passes between the said rollers.

5 The roller 79 is driven by power transmitted through the bevel gears 88 and 89, the former being secured on the driven shaft 25. A telescopic shaft having members 90 and 91 operatively connects universal joints 92 and 93, the latter of which is directly connected with the shaft 94 on which the roller 79 is mounted. The roller 78 is mounted in bearings on a rocking frame 95, the tail whereof is suspended on compression springs 96. The springs 96 rock the frame 95 so that pressure is constantly maintained by the roller 78 on the roller 79. It is evident that as soon as the folded member A is delivered to the said rollers the rotation of 10 the roller 79 will carry the member A between the rollers 78 and 79 under the pressure of the spring 96, and that, when in the course of the operation the edge F having its coating of adhesive overlies the short 15 standing portion G the edge F is pressed thereon to cover the same. This action is best shown by reference to Fig. 11, which indicates the position of the parts as the product of the machine spreads between the 20 rollers 78 and 79; while in Fig. 12 the product is shown as it is delivered from between the said rollers and from the machine. The function of the machine ceases at this point. Thereafter an operative unfolds the product 25 to dispose the same in the manner shown in Fig. 13, in which position the casing is ready to receive the tray for which it is provided.

It will be understood that the cam dwells 30 76 permit the spring 27 to hold the platen in its lowermost position until the plate 80 has been retracted from the upward path of the said platen. Also, the cam 24 is timed so that the rollers 78 and 79 will have removed 35 the folded product from the path of the said platen prior to the wheel 26 riding to the highest level of the said cam 24 to lift the platen 20 to its initial receiving position. From this point the operation above de- 40 scribed is repeated.

The shaft 25 which furnishes power to the mechanism disclosed is driven by power imparted to a pulley 97; or, if desired, the said shaft is directly driven by some independent 45 motive power.

Claims.

1. A machine as characterized comprising a table having an opening therein shaped 50 in correspondence with the product of the machine, the edges of said opening being adapted for the up-turning of the overhanging edges of the covering material of said product; a platen approximately filling said opening; a plunger foot corre-

sponding in shape to said platen; means for moving said foot into engagement with said platen to hold said product thereon; a wiper mechanism, embodying wiper members and a mechanism for operating the same, pivoted to move the operating ends thereof over the said up-standing edges of said covering material to fold the same upon said product coöperating rotary pressing members; means for moving said plunger 70 foot and platen coöperatively downward through said opening to aline said product with the coöperating rotary pressing members; and means for advancing said product to said rotary pressing members for spreading the end of the covering material on the adjacent edge of the product prior to the delivery thereof from the machine.

2. In a machine for folding the adhesive edges of a covering material over a relatively rigid product scored to be bent on predetermined lines, the combination of an apertured table, a mechanism for upturning the edges of said adhesive material and for folding and for over-turning the same on said product, said mechanism embodying a holding platen and plunger foot for engaging said product and a plurality of rocking wiping arms having wipers adapted for rubbing the adhesive edges 95 upon said product, and a mechanism for operating said wipers simultaneously.

3. In a machine as characterized, the combination of an apertured table, the aperture being shaped in correspondence with the product of the machine; a vertically reciprocated platen approximately filling the aperture in said table; a reciprocating mechanism coöperating with said platen having a plunger and a foot thereon for holding the product on said platen, and means coöperating for moving said platen and said plunger in unison without diminishing the hold of said plunger and platen on said product to a delivery position below said table; a transfer mechanism embodying a loosely reciprocating member for extension over said platen for extracting the product therefrom; and a delivery mechanism embodying a plurality of delivery rollers for withdrawing said product from said platen and for discharging.

4. In a machine as characterized, the combination of an apertured table, the aperture being shaped in correspondence with the product of the machine; a vertically reciprocated platen approximately filling the aperture in said table; a reciprocating mechanism coöperating with said platen having a plunger and a foot thereon for holding the product on said platen, and means coöperating for moving said platen and said plunger in unison, without diminishing the hold of said plunger and platen on said product, to a delivery position be- 130

low said table; a transfer mechanism embodying a laterally reciprocating member for extension over said platen for extracting the product therefrom; a delivery mechanism embodying a plurality of delivery rollers for withdrawing said product from said platen and for discharging; and a co-ordinated operating mechanism for said

members, said mechanism embodying a series of cams and a transmission device 10 operatively connecting said members and said cams for operating said members in time and correspondence.

WILLIAM HUGHES.
OTTO R. BIELER.
